UNITED STATES PATENT OFFICE.

HAROLD N. MOORE, OF KEARNEY, NEBRASKA.

INTERNAL-COMBUSTION ENGINE.

Application filed May 5, 1924. Serial No. 711,173.

To all whom it may concern:

Be it known that I, HAROLD N. MOORE, citizen of the United States, residing at Kearney, in the county of Buffalo and State 5 of Nebraska, have invented certain new and useful Improvements in Internal-Combustion Engines, of which the following is a specification.

This invention relates to improvements 10 in internal combustion engines and more particularly to an improved rotary valve mechanism for such engines.

The invention seeks, among other objects, to provide a valve mechanism wherein the 15 valves employed will be light in weight and efficiently lubricated.

A further object of the invention is to provide a mechanism wherein oil will be constantly circulated through the valves from 20 end to end thereof for thus maintaining the valves cool at all engine speeds.

Another object of the invention is to provide a mechanism wherein the valves will be yieldably held to cooperate with the walls of 25 the valve chambers in such manner that the valves will effectively seal the ports of the engine cylinders and wherein the tensioning devices employed in conjunction with the valves will also serve to limit the valves 30 against endwise movement.

And the invention seeks, as a still further object, to provide a mechanism wherein the valves may be readily assembled upon the engine head and wherein the valves and 35 head may be detached from the engine block as a unit.

Other and incidental objects will appear hereinafter.

In the drawings:

40 Figure 1 is a side elevation showing an internal combustion engine embodying my improved valve mechanism, parts being broken away and illustrated in section.

Figure 2 is a fragmentary vertical sectional view on the line 2—2 of Figure 1, looking in the direction of the arrows,

45 Figure 3 is a sectional view on the line 3—3 of Figure 1, looking in the direction of the arrows, and showing the mechanism for rotating the valves,

50 Figure 4 is a detail sectional view on the line 4—4 of Figure 1, looking in the direction of the arrows, and particularly showing one of the tensioning devices for the valves,

55 Figure 5 is a longitudinal sectional view

taken medially through one of the valves, and

Figure 6 is a detail perspective view showing the lubricant distributing chamber for the valves.

In carrying the invention into effect, I employ an engine block 10 and bolted to the block is a head 11, the head as well as the block being suitably water-jacketed. In the present instance, I have shown the invention in conjunction with a four cylinder engine but as will, of course, be understood, the invention is equally applicable to engines having either a greater or less number of cylinders. Near opposite sides thereof, the head 11 is, as best shown in Figures 1 and 2 of the drawings, provided from end to end with parallel valve chambers 12 having horizontal ports 13 at each of the cylinders of the block and communicating 75 with the valve chambers at such ports are intake and exhaust manifolds 14 and 15 respectively. As brought out in Figure 2, the ports 13 are located below the axes of the valve chambers and formed in the block 11 80 between the inner ends of the ports, are vertical openings 16 internally threaded at their upper ends to accommodate spark plugs, as conventionally shown at 17.

Journalled in the valve chambers are tubular intake and exhaust valves 18 and 19 projecting at the forward ends of the block and fixed upon the forward extremities of said valves are sprockets 20. The crank shaft of the engine is indicated at 21, the shaft of an approved generator at 22, and the shaft of an approved water pump at 23. Projecting from the engine block above the crank shaft 21 is a stub shaft 24 and mounted upon said shafts are sprockets 25 95 about which is trained a sprocket chain 26. The stub shaft 24 carries a second sprocket 27 and trained around said sprocket and around the sprocket 20 of the valves is a sprocket chain 28, the several sprockets being so proportioned that the valves will be rotated at half the speed of the engine crank shaft and while I have shown the use of sprockets and sprocket chains for driving the valves, still, if preferred, other mechanism may be substituted in lieu thereof. Formed on the engine block as well as the engine head near the forward ends thereof, are flanges 29 seating a gear case 30 having flanges 31 bolted to the flanges 29. As 110

shown in Figure 3, the gear case 30 is also bolted to the crank case 32 of the engine so that the gear case thus encloses the sprockets and sprocket chains employed for rotating the valves and provides a collecting and conducting chamber common to both valves for returning oil discharged at the forward ends of the valves back into the crank case at its forward end.

As shown in detail in Figure 5 of the drawings, the valves 18 and 19 are of uniform major diameter throughout their length and, as will be observed, the valves are indented at properly spaced points to form suitably located external passages 33 to register with the ports 13 of the valve chambers. The valves are further provided between said passages as well as near the ends of the valves, with annular grooves 34 which coincide with vertical openings 35 through the engine head 11 and freely received in said openings to lie partially within said grooves and partially within the lower ends of the openings, as shown in Figure 4, are the balls 36 of the tensioning devices provided in conjunction with the valves. Overlying said balls are followers 37 from which rise stems 38 and screwed into the openings 35 are cap bolts 39 bored to slidably accommodate said stems. Bearing between the inner ends of said cap bolts and the followers 37 are springs 40, the tension of which may be varied by adjusting said bolts, and arranged upon the bolts are lock nuts 41 securing the bolts in adjusted position. The followers 37 will thus be pressed downwardly against the balls 36 which, in turn, will press downwardly upon the valves so that the valves will, at all times, be yieldably held in contact with the bottom portions of the valve chambers to effectually seal the ports 13 as the valves are revolved. Furthermore, attention is directed to the fact that the balls 36 will coat with the walls of the grooves 34 for locking the valves against endwise movement. As will, of course, be understood, the passages 33 of the valves are so spaced with respect to each other circumferentially of the valves that the intake and exhaust ports of the cylinders will be opened and closed at the proper time as regards the travel of the engine pistons.

Screwed into the rear ends of the valves are reduced nipples 42 and arranged to cooperate with said nipples is an oil distributing chamber 43. Projecting from the chamber is an overhanging flange 44 which is bolted to the engine head 11 and extending from the inner side wall of said chamber are, as shown in Figure 6, spaced nipples 45 fitting over the nipples 42 of the valves. The nipples 45 are externally threaded to accommodate nuts 46 and enclosed by said nuts are packings 47. Thus, the nuts may be adjusted for pressing the packings

against the beveled outer end edges of the nipples 45 for maintaining sealed joints between the distributing chamber and the valves. Driven by the generator shaft 22 is an appropriate oil pump 48 and leading from said pump is a pipe 49 attached to a nipple 50 depending from the chamber 43. The pump 48 is connected with the engine crank case to receive oil therefrom, so that, as will be seen, while the engine is running, a constant flow of oil will be forced into the chamber 43 and thence through the valves 18 and 19 to discharge into the gear case 30 for return to the crank case. The valves will thus be effectually cooled at all engine speeds and formed through the walls of the valves are suitably spaced minute oil passages 51 through which oil may seep for lubricating the valves. Since oil is thus liberated into the valve chambers, the valves are, as shown in Figure 1, provided at their rear end portions with spiral grooves 52 which, as the valves are revolved, will pick up any excess oil at the rear ends of the valve chambers and feed such oil forwardly along the valves to thus prevent the discharge of oil at the rear extremities of the chambers.

Having thus described the invention, what I claim is:

1. In an internal combustion engine, a cylinder head, rotatable tubular intake and exhaust valves carried thereby and projecting at one end of the head, an oil distributing chamber common to the valves, and means for delivering oil to said chamber to circulate through the valves, the chamber being provided with means supporting said chamber in spaced relation to the said end of the head to communicate with the projecting ends of the valves and forming a cover overlying said ends.

2. In an internal combustion engine, a cylinder head having valve chambers opening through the ends of the head, tubular intake and exhaust valves rotatably mounted in said chambers, an oil distributing chamber common to the valves, means for delivering oil to said distributing chamber to circulate through the valves, the valves being provided with passages for liberating oil into said valve chambers, and means carried by the valves near the rear ends thereof for feeding oil in the chambers away from the rear ends of said chambers as the valves revolve.

3. In an internal combustion engine, a cylinder head having valve chambers opening through the ends of the head, tubular intake and exhaust valves rotatably mounted in said chambers, an oil distributing chamber common to the valves, and means for delivering oil to said distributing chamber to circulate through the valves, the valves being provided with passages for liberating

oil into said valve chambers and being further provided at their rear end portions with grooves for feeding oil in the chambers away from the rear ends of the chambers as the valves revolve.

4. In an internal combustion engine, a cylinder head, rotatable tubular valves carried thereby and provided at their rear ends with nipples, an oil distributing chamber supported in spaced relation to the head and having nipples fitting over the nipples of the valves, packing glands carried by the latter nipples forming sealed joints between the nipples, and means for delivering oil to said chamber to circulate through the valves.

5. In an internal combustion engine, a cylinder head having valve chambers and provided at the upper sides of said chambers with openings, tubular valves journaled in said chambers and provided with annular grooves to coincide with said openings, balls freely received in the openings to bear in said grooves locking the valves against endwise movement, followers coacting with said balls and provided with stems, plugs adjustable in said openings and bored to slidably receive said stems, and springs bearing between the plugs and the followers pressing the balls downwardly against the valves and urging the valves downwardly against the bottom portions of the valve chambers.

6. In an internal combustion engine, a cylinder head having a valve chamber, a valve journaled in said chamber, and means having rolling engagement with the valve and locking the valve against endwise movement as well as pressing the valve downwardly against the bottom portion of said chamber.

7. In an internal combustion engine, a cylinder head having a valve chamber, a valve journaled in said chamber and provided with an annular groove, and a spring pressed anti-friction device fitting in said groove locking the valve against endwise movement as well as pressing the valve downwardly against the bottom portion of said chamber.

8. In an internal combustion engine, a cylinder head, rotatable tubular valves carried thereby and provided at corresponding ends thereof with nipples, an oil distributing chamber having an overhanging flange fixed to one end of the head to overlie said nipples and supporting the chamber in spaced relation to the head to communicate with said nipples, and means for delivering oil to said chamber to circulate through the valves.

In testimony whereof I affix my signature.

HAROLD N. MOORE. [L. s.]
